UNITED STATES PATENT OFFICE.

SAMUEL JOHNSON, OF CLINTON, MISSOURI.

WINDOW-SASH GUIDE.

SPECIFICATION forming part of Letters Patent No. 596,068, dated December 28, 1897.

Application filed March 22, 1897. Serial No. 628,803. (No model.)

To all whom it may concern:

Be it known that I, SAMUEL JOHNSON, a citizen of the United States, residing at Clinton, in the county of Henry and State of Missouri, 5 have invented a new and useful Window-Sash Guide, of which the following is a specification.

This invention relates to window - sash guides, and has for its object to provide a 10 simple, economical, and efficient guiding-strip for window-sashes and screen-frames, the said strips being each formed in a single piece of sheet metal, from which integral ears are struck out and adapted to embrace the edges 15 of the sash for maintaining the strip in proper relation thereto. The strip is intended to render a window water, wind, and burglar proof and at the same time to prevent rattling of the sashes or screens, as the case may be.

20 To this end the invention consists in a guiding-strip for window-sashes, &c., embodying certain novel features and details of construction, as hereinafter fully described, illustrated in the drawings, and incorporated in the 25 claims.

In the accompanying drawings, Figure 1 is a perspective view of a window-frame, &c., showing the manner of applying the improved guiding-strips to the sashes. Fig. 2 is an enlarged detail horizontal section taken at one 30 side of the frame and showing the sliding engagement between the sashes and frame. Fig. 3 is a detail perspective view of a portion of a double guiding-strip constructed in accordance with this invention. Fig. 4 is a 35 plan view of a sheet-metal blank from which a double strip is formed. Fig. 5 is a view in elevation of a portion of a window - frame, showing guiding-strips applied to a screen-frame and illustrating a modification of the 40 invention. Fig. 6 is a detail horizontal section taken at one side thereof. Fig. 7 is a detail perspective view of a single guiding-strip. Fig. 8 is a plan view of a blank from which a 45 single strip is formed.

Similar numerals of reference designate corresponding parts in the several figures of the drawings.

The guiding-strips contemplated herein are 50 each formed from a single sheet-metal blank of oblong form. In fashioning the double

strip the metal blank is creased and bent upon the longitudinal lines 1 to form the spaced flanges 2, which project at right angles to the main body of the strip. At suitable intervals 55 along the length of the strip attaching-ears 3 are formed for securing the strip as a whole to the window-sash or screen-frame. These ears are formed by making spaced parallel 60 incisions 4, extending transversely of the strip between the bends 1, after which a central longitudinal incision 5 is made, extending between the incisions 4. The metal bounded by these incisions is now bent back from the main body of the strip, thus forming the ears 65 3, the said ears lying in substantially the same plane with the flanges 2 and embracing the sides of the frame-bars of the window-sash or screen-frame, as shown in Figs. 1 and 2, being secured by means of screws or other 70 fasteners 6. The inner adjacent surfaces of the stiles or jambs of the window-frame are provided with spaced vertical grooves, in which the laterally-projecting spaced flanges 2 are slidingly received.

75 In Figs. 5 to 8 of the accompanying drawings is illustrated a modification of the invention, and a single guiding-strip is shown. The single guiding-strip is also formed in a single piece of sheet metal, the same being 80 bent upon the longitudinal lines 7 to form at one side the laterally-projecting flange 2 and at the other side an oppositely-projecting flange 8, which is adapted to lie against one of the side surfaces of the window-sash or 85 screen-frame and to be secured by fasteners in the same manner as the attaching-ears 3 above referred to. In the case of the single strip only one row of ears is provided, and these are formed by making U-shaped or 90 three-sided incisions 9 at suitable intervals throughout the length of the strip, the metal bounded by such incision being bent or extended back in the plane of the flange 2 and adapted to lie upon the opposite side of the 95 sash or frame from the flange 8.

From the foregoing description it will be seen that either the double or the single strip is formed in one piece, the attaching ears or flanges, as the case may be, being struck up 100 as integral parts of the strip. The double strip is especially designed for window-sashes,

while the single strip is more desirable for screen-frames. By traversing grooves in the window-frame the laterally-projecting flanges 2 effectually exclude wind, rain, dust, cold air, &c., obviate rattling of the sashes, and by locating the flanges 2 in the plane of the inner surface of the sash the latter cannot be removed, even though the usual window-stops be detached by a person endeavoring to obtain access to a house.

Having thus described the invention, what is claimed as new is—

1. A guiding-strip for window-sashes, screen-frames, &c., formed from a sheet-metal blank in one piece, the said strip comprising a main body portion, a laterally-projecting flange bent at right angles thereto and extending from one side of the body portion, and a series of attaching-ears extending from the opposite side of the body portion and struck from the material composing the strip and adapted to be secured to a sash

or frame upon one side, substantially in the manner described.

2. A guiding-strip for window-sashes, screen-frames, &c., formed from a single sheet-metal blank in the form of an oblong strip, the same comprising spaced flanges projecting at right angles to the main body of the strip, from one side of the same, and attaching-ears struck from the main body of the strip and forming integral parts thereof and projecting from the opposite side of the same, the said ears being spaced apart and adapted to embrace the edge of a sash or frame, substantially in the manner specified.

In testimony that I claim the foregoing as my own I have hereto affixed my signature in the presence of two witnesses.

SAMUEL JOHNSON.
